WIRE-STRIPPING TOOL

Clyde C. Johnson, 10213 7th Ave., Inglewood, Calif.

Filed Dec. 4, 1962, Ser. No. 72,713

Term of patent 14 years

(Cl. D54—13)

FIGURE 1 is a perspective view of a wire-stripping tool having a slidable cover member, the slidable cover member being shown in its closed position;

FIGURE 2 is a perspective view of the wire-stripping tool, with the slidable cover member being shown in a separated position;

FIGURE 3 is an elevational view of the right side of the wire-stripping tool of FIGURE 1;

FIGURE 4 is a rear elevational view of the wire-stripping tool of FIGURE 1;

FIGURE 5 is an elevational view of the left side of the wire-stripping tool of FIGURE 1;

FIGURE 6 is a top plan view of the wire-stripping tool of FIGURE 1, the bottom being identical; and

FIGURE 7 is a front elevational view of the wire-stripping tool of FIGURE 1.

The undisclosed left side of the wire-stripping tool shown in FIGURE 2 is identical to the disclosed right side.

I claim:

The ornamental design for a wire-stripping tool, substantially as shown and described.
